US0D1100744S

(12) **United States Design Patent** (10) **Patent No.:** **US D1,100,744 S**
Xu (45) **Date of Patent:** **** Nov. 4, 2025**

(54) **DRONE**

(71) Applicant: **Shantou Xingdu Intelligent Control Technology Co., Ltd.**, Guangdong (CN)

(72) Inventor: **Chuyong Xu**, Guangdong (CN)

(73) Assignee: **Shantou Xingdu Intelligent Control Technology Co., Ltd.**, Shantou (CN)

(**) Term: **15 Years**

(21) Appl. No.: **29/983,713**

(22) Filed: **Jan. 11, 2025**

(51) LOC (15) Cl. **12-06**

(52) U.S. Cl.

USPC **D12/16.1**

(58) **Field of Classification Search**

USPC D12/16.1, 328, 326, 344, 345, 1–4, 174, D12/319–325, 327, 329–343; D21/301, D21/436, 441, 443, 444, 446, 447, 448, D21/449, 450, 451, 452, 453
